UNITED STATES PATENT OFFICE.

MYERS A. GARRETT, OF CHICAGO, ILLINOIS.

TANK-CAR.

1,087,939.

Specification of Letters Patent.

Patented Feb. 24, 1914.

Application filed July 5, 1913. Serial No. 777,517.

To all whom it may concern:

Be it known that I, MYERS A. GARRETT, a citizen of the United States, residing at Chicago, in the county of Cook and State 5 of Illinois, have invented certain new and useful Improvements in Tank-Cars, of which the following is a specification.

Heretofore the common practice has been to construct tank cars by forming a supporting frame having center sills, and mounting the tank proper, which generally has been of a cylindrical shape, upon the frame and above the center sills. For tanks of limited capacity such construction was, 10 for the most part, unobjectionable. With the increase in the size of the tank the center of gravity was raised so far that on curves the car tipped over and many wrecks resulted. Further, in buffing the frame has 15 often been shifted relative to the tank, or the latter shifted relative to the former, due to the inertia of the tank and its contents, or to the momentum of the same relative to the frame. Still further, no provision has 20 been made in construction for the allowance of expansion of the tank when loaded with hot material, such as hot lard, hot 25 tar, etc.

The main object of my invention is to ob- 30 viate the objections appertaining to tank cars constructed as described, and as otherwise constructed, and to provide a tank car of relatively large capacity, relatively low center of gravity when loaded, and with a tank 35 made separate from the frame and removably anchored thereto in such a way that the tank and frame shall preserve their fixed relative positions each to the other under all conditions of service.

40 A further object is the production of a tank car so constructed as to provide for expansion without injurious results to the structure, and one in which the strains of drawing and buffing shall be transmitted 45 mainly around the lower sides of the central part of the tank.

With these ends in view, my invention consists in constructing a frame with strong and rigid ends, especially in front of the 50 body bolsters, where the draft and buffing gears are attached, by means of two parallel flanged metallic beams, which beams b, c k of the body bolsters are spread apart to leave a relatively large unobstructed space 55 at the center, uniting said beams by tension members, and providing trusses for the

same, and supporting upon said frame a tank, the center lower part or wall of which shall occupy a position below the horizontal plane of the body bolsters and relatively 60 near the road bed.

Further, it consists in uniting the said main flanged beams at their central portions by curved or bent bars or supports whereby in buffing the strains upon the said flanged 65 beams tending to spread them will be transmitted to said bars or supports and exert a lifting force or energy upon the bottom of the tank.

Finally, it consists in certain novelties of 70 construction and combinations of parts as herein set forth and claimed.

The accompanying drawings illustrate one complete example of the embodiment of the invention and two modifications of tension 75 members back of the bolsters, constructed according to the best modes of procedure I have so far devised for the purpose.

Figure 1 is a side view in elevation of a tank car embodying my invention. Fig. 2 80 is a cross section of Fig. 1 on line x, showing one of the body bolsters in elevation and the heel pieces attached to the under side of the tank. Fig. 3 is a top plan view of the frame, the footboards being removed. 85 Fig. 4 is a fragmentary section on one side at the longitudinal center, showing the detachable connection of the tank to a side sill. Figs. 5 and 6 are detail views, showing different dispositions of the tension 90 members back of the bolsters.

The main elements of the frame are two flanged metallic beams or sills A A, in this instance angle beams 8"x8"x11", extending from end to end of the frame. At the ex- 95 treme ends B B they are relatively near together and parallel and adapted to receive the draft and buffing gears, then they are bent apart or spread at angles each to the other for a short distance beyond the body 100 bolsters and thereafter at their middle portions are disposed parallel and constitute side sills. Stiffening plates D D are securely riveted to the parallel end portions of the beams in front of the bolsters, and the ex- 105 treme ends are provided with castings C C to receive the impact from the coupler horns in buffing, the said castings being secured to the beams and to the end sills E E by rivets or bolts in a well known way. Supports F F 110 for the footboards are riveted to the flanges of the sills at the sides and the footboards

are bolted to these supports and to the ends G G of the end sills. The body bolsters H H are in this instance each of metal I-shaped in cross section and each cast with 5 two recesses I I or obliquely disposed slots to receive one flange of each angle iron sill, the slots being bounded by flanges extended from the vertical web of the I beam on each side thereof and below the top flange, as 10 clearly shown by dotted lines in Fig. 3 and full lines Fig. 2, through which and the flanges of the angle iron sills rivets are passed, also clearly indicated by dotted lines. Tension members J J, in this instance channel beams, unite the main sills back of the 15 bolsters. They may be disposed as shown in Figs. 1 and 3, where the web of the beam is obliquely disposed at an angle of about 45 degrees, or in vertical or horizontal positions as shown by Figs. 5 and 6, as desired, to fit or match the outline of the lower portion of the tank adjacent thereto. Uniting the main beams or sills at their central 20 portions are two downwardly curved supporting members—in this instance channel beams K K with the ends riveted to the webs of the sills. The side trusses consist at each 25 side of a horizontal metallic bar L and two obliquely disposed bars M M secured to the webs of the sills and to the central channel 30 beams K K, as shown in Figs. 1 and 3.

The tank N is supported at its ends by the body bolsters, and intermediate its ends by the tension members J J, the curved 35 members K K, and the sills. To prevent longitudinal displacement of the tank relative to the frame, or vice versa, angle plates O O fitting against the outer vertical surfaces of the body bolsters and riveted to the 40 bottom surfaces of the ends of the tank are provided, as shown in full lines, Fig. 2. These angle plates may be of any desired length; for instance, of the length shown by dotted lines, Fig. 3, which illustrates the 45 locations of the plates relative to the top flange of the body bolster. To anchor the tank still more securely, angle irons P P are riveted to each side of the tank and their flanges secured by bolts to the flanges of 50 the sills, as shown by Figs. 1 and 4.

The tank may be of any shape desired with the downwardly extended portion Q, which may be provided with a single or double discharge outlet having a valve or valves R 55 of any suitable type for discharging the contents to one or both sides of the track. The bottom of the tank should incline toward the discharge outlets, as shown by Fig. 1, to facilitate the complete discharge of 60 the contents. The tension members J J may be disposed relative to the under surface of the tank, as shown in Figs. 1 and 3, or in Figs. 5 and 6, or otherwise, so as to support part of the weight of the tank and also 65 prevent the longitudinal movement of the

same relative to the frame, the flat sides of the channels bearing against the surfaces of the tank, thus coöperating with the other described means for the same purpose, and, furthermore, distributing the strains. If 70 desired, two U-shaped channels S S may be extended over the top of the tank adjacent the center for the purpose of more securely anchoring the same to the frame.

The car comprising the frame and tank 75 connected therewith, as shown and described, has a relatively low center of gravity when the tank is filled with oil or other liquid and thus it will not tip over on curves. The tank can easily be removed from the frame 80 when repairs of either the tank or frame are necessary. The frame itself is so constructed that it will effectively resist strains imparted from any direction, and especially those incident to drawing and buffing, by reason of 85 the presence of the end castings and the plates and body bolsters, and the tank itself is securely anchored against endwise movements, especially by the heel plates or angles O O. Moreover, the expansion and 90 contraction of the tank under the action of heat will not seriously affect the same or the frame.

In buffing the strains not absorbed by the rigid end portions, the castings, end cover 95 plates and sills below the same will be transmitted through the obliquely disposed parts of the sills to the parallel intermediate portions thereof and any strains tending to spread the sills will be transmitted to the 100 members J J and K K and be transformed into lifting energy upon the bottom of the tank, thus preventing an excessive bending of the sills from their normal parallel positions. The tie members S S will also counteract the upward strains imparted to the supports K K and distribute the strains.

Obviously, in the embodiment of the invention minor changes may be introduced, such as the addition of draft beams to the 110 ends of the sills, the substitution of other flanged beams of I or channel or other shape for the angle beam sills, and a different form of side truss may be selected, without constituting substantial departures.

What I claim is:

1. A car frame comprising body bolsters, two main flanged metallic members extending from end to end of the frame, the extreme adjacent ends thereof in front of the 120 bolsters being parallel and the portions intermediate the ends spread apart, to constitute the side sills and the central portions thereof located in planes outside of but parallel with the said extreme adjacent ends, 125 means uniting the extreme adjacent parallel ends of the members, and tension members uniting the intermediate portions of said members; whereby an open space is provided between the body bolsters and the spread in- 130

termidate portions to receive and support a tank.

2. A car frame comprising two main flanged metallic members extending from end to end of the frame, the extreme adjacent ends thereof being parallel and the portions intermediate the ends spaced apart to lie in planes parallel with but outside the planes of the said extreme adjacent ends so

10 as to constitute side sills, cover plates riveted to the adjacent parallel ends of the members, end sills, castings in connection with the end sills adjacent to the said plates, body bolsters located between the said extreme adjacent ends of the main members and the central spaced apart portions thereof, and tension members uniting the intermediate portions of said members.

3. A car frame comprising two main flanged metallic members extending from end to end of the frame, the extreme adjacent ends thereof being parallel and the portions intermediate the ends spaced apart, means uniting the extreme adjacent parallel ends of the members, body bolsters having slots within which the flanged members are seated and anchored, and tension members uniting the intermediate portions of said members.

4. A car frame comprising two main flanged metallic members extending from end to end of the frame, the extreme adjacent ends being parallel and the portions intermediate the ends spaced apart to constitute the side sills and to lie in planes outside the parallel planes of the extreme adjacent ends, means uniting the extreme adjacent parallel ends of the members, body bolsters to which said members are secured, curved tension members uniting the intermediate portions of said members, and truss members united to the curved tension members and to the spread side sill portions of the said main flanged members.

5. A car frame comprising two main flanged metallic members with the extreme adjacent ends united by suitable means, the central portions being spaced apart to lie in planes outside the extreme adjacent ends and constituting the side sills intermediate the bolsters to which said members are secured, curved supporting members uniting the side sill portions of said members, truss members in connection with the side sill portions and the said supporting members, and tension members back of the bolsters and serving as bearings for the bottom of the tank.

6. The combination with a frame comprising two main members extending from end to end of the frame having the extreme adjacent parallel ends united and the central portions spread apart to lie in longitudinal planes outside the planes of the ex-

treme parallel ends so as to constitute side sills, and provided with supports extending 65 at right angles to the main members and uniting the same, of body bolsters to which the main members are secured, a tank with a lower portion extended below the plane of the body bolsters, and means for anchoring 70 the tank to the frame.

7. The combination with a frame comprising two main members extending from end to end of the frame having the extreme adjacent parallel ends united and the central 75 portions spaced apart to lie in longitudinal planes outside the planes of the extreme adjacent parallel ends so as to constitute side sills and provided with cross supports, of body bolsters to which the main members 80 are secured, a tank with a lower portion extended below the plane of the body bolsters, and means, as heels secured to the under surface of the tank, and engaging the body bolsters for anchoring the tank to the frame. 85

8. The combination with a frame comprising two main members extending from end to end of the frame having the extreme adjacent parallel ends united and the central portions spaced apart to lie in planes outside 90 the planes of the extreme adjacent parallel ends to constitute side sills and provided with supports, of body bolsters to which the main members are secured, a tank with a lower portion extended below the plane of 95 the body bolsters, and means connected to the tank and the side sills for anchoring the tank to the frame.

9. The combination with a car frame having two main flanged longitudinal metallic 100 members united at the extreme adjacent parallel ends and bent apart intermediate their ends, bent supporting members uniting the central portions of said main members, body bolsters, and tension members back of 105 the body bolsters, of a tank with a downwardly extended central part, said tank being supported by the body bolsters, the bent supporting members, tension members and the central portions of the said main members to which main members said tank is detachably secured.

10. A car frame comprising two main flanged metallic members extending from end to end of the frame, the central portions 110 thereof being spread apart and the adjacent ends substantially parallel, means for uniting the extreme ends of said members, and slotted bolsters, the main members being secured within the slots in said bolsters. 115

In testimony whereof I affix my signature in presence of two witnesses.
